UNITED STATES PATENT OFFICE.

ARTHUR REGINALD ANGUS, OF NEUTRAL BAY, NEAR SYDNEY, NEW SOUTH WALES,
AUSTRALIA.

RUNNING-GEAR OF RAILWAY-CARS.

1,033,294.

Specification of Letters Patent.

Patented July 23, 1912.

Application filed November 13, 1906. Serial No. 343,216.

To all whom it may concern:

Be it known that I, ARTHUR REGINALD ANGUS, of Barry street, Neutral Bay, near Sydney, in the State of New South Wales 5 and Commonwealth of Australia, solicitor, have invented Improvements in the Running-Gear of Railway-Cars, of which the following is a specification.

This invention refers to the running gear 10 of railway cars, carriages, wagons and trucks (herein referred to severally and collectively as railway cars).

It has been specially devised to provide devices for preserving the gage of the wheels 15 of the divided axles, while at the same time allowing them independent revolution and for insuring the preservation of axial line and also to place the wheels and semi-axles in equilibrium or as near thereto as may be.

20 In carrying this invention into practice the four bearings of the semi-axles are rigidly connected together by means of a frame work of steel or iron constructed as hereinafter described. The bearings are so

25 constructed that the brasses entirely encircle the semi-axles being in close contact therewith and are rigidly bolted to the abovementioned frame. By brasses I mean the brasses made from gun metal or other material in

30 which the axles revolve in direct contact therewith. By bearings I mean the blocks placed on the brasses and being in direct contact therewith, which bearings I indicate at 16. This framework is preferably

35 rectangular in shape (but may be bent or curved provided that the four bearings of a pair of corresponding semi-axles are rigidly connected by a rigid framework) and surrounds the wheels rigidly connecting

40 the four bearings of a pair of corresponding semi-axles. This framework is preferably constructed in one piece and consists of four cross bars or stays and two girders or transverse bars and sufficiently strong to

45 resist the maximum strain likely to be experienced and tending to disturb the axial line. Each bar or stay is preferably disposed horizontally at right angles to the line of the semi-axles and with their ext-

50 tremities equidistant therefrom. These bars or stays are of equal length being somewhat longer than the diameter of the wheels. The two girders lie parallel to each other and to the line of the semi-axles. Each bar or

55 stay completely encircles the bearings.

It being essential to obtain the principle that the framework through each bar or stay should prevent the semi-axles from having any other action than that of rotation in their bearings except end thrusts of semi-axles, I seek to prevent the framework as a whole from responding to the action of the springs of the car up or down by the use of a rigid frame or framework, rigid as a whole, which is rigidly affixed to its 60 bearings and brasses, the brasses being in close contact with the divided axles and thus seek to preserve the axial line of each pair of semi-axles. I also seek to assist the rigidity of the frame and, at the same time, 65 reduce the leverage action of the divided axles on the frame by placing each wheel of the car adjacent to the outermost bearings, that is to say, each wheel is placed as close to the outermost bearings as the construction of the car will permit. Each corresponding cross bar or stay on one semi-axle is placed or affixed equidistantly from its wheel so as to insure the equilibrium of 70 each wheel and semi-axle. Each outer and inner bar of the frame is affixed as close to the wheel common to both as the construction of the car will permit, so as to reduce the leverage action incident to the divided axles and frame, and to place the parts concerned 75 in equilibrium. By the particular construction of the rigid frame, rigidly affixed to its brasses and brasses and the equilibrium of the parts as near as may be, I seek to further assist in retaining the axial line of each 80 pair of semi-axles.

The bearings have top and bottom brasses encircling the semi-axles and are rigidly held together between the bar or stay and a bridge piece being bolted together. The inner surfaces of the brasses have cut therein a groove of sufficient depth to allow a collar loosely attached upon the semi-axles to revolve therein the lower or bottom brass containing an oil well wherein the collar dips. A tube or tubes containing cotton or other capillary fabric leads from the bottom of the oil well into the oil cup above the bearing so as to convey thereto the surplus oil from said oil well. The outer bearings have also attached boxes containing a U-shaped keeper fitting over a groove on the semi-axles as is usual but enough play should be allowed in the groove of semi-axle to permit of reduced internal end of one 100 105 110

semi-axle to abut against the end of socket in the other semi-axle.

The springs supporting the body of the railway car may rest upon the top of the 5 bearings in the bars or stays and preferably additional coil or helical springs may be used and are affixed upon the rigid frame at the junction of the bars or stays and girders and the body of the carriage may have 10 sockets to receive the top ends of said helical springs. To the framework may also be attached the hangers supporting the brake bars. To further assist in preserving the axial line of two corresponding semi-axles 15 the internal end of one of the corresponding semi-axles is bored out to a depth corresponding to the diameter of the axle and has an annulus of one third of the diameter of axle having a brass bush. The internal 20 end of the other semi-axle is reduced to fit into the brass bush contained in the corresponding semi-axle the inner end of each semi-axle abutting, or nearly abutting, against its corresponding semi-axle, so as to 25 preserve the gage of the wheels.

A cover or box is fitted over the junction of the two semi-axles and supported in any convenient manner say by cross bars bolted to the bars or stays and is constructed in 30 two halves that are bolted together by means of flanges. The bottom half of the box acting as an oil well has a tube leading therefrom containing cotton or other fabric so as to convey the oil back into the oil cup 35 secured to the top half of the box.

In the case of railway cars provided with bogies a framework is constructed for each pair of semi-axles as hereinbefore described. The two nearest girders of two adjacent 40 frameworks of one bogie being close together are connected by bolts or plates or stays and sufficient allowance being made at the joints for any radial action. These connecting plates, bolts or stays may carry the 45 springs supporting the body of the car.

The term "divided axle" used in connection with these improvements means or is synonymous with the term "a pair of semi-axles" also with the term "two corresponding semi-axles". Each divided axle has therefore two parts, each part of a divided axle—though independent of the other part thereof so far as rotation is concerned—is assumed to be in a straight line with the 55 other or practically so, which I term "the axial line". But in order that my invention may be understood reference will now be made to the drawings, wherein—

Figure 1 is a perspective view of a truck 60 having embodied therein the rigid frame work. Fig. 2 is a similar view of the rigid framework. Fig. 3 is a perspective view of a truck the body being supported by helical springs attached to the rigid framework 65 said frame also carrying the brake bars.

Fig. 4 a perspective view of a bogie with rigid framework, and the method of connecting them. Fig. 5 a perspective view of the rigid framework of a bogie and the method of connecting. Fig. 6 a section showing the joining together of the two rigid frameworks. Figs. 7 and 8 are sections through the intermediate and end bearings respectively. Fig. 9 a perspective view of the junction of the semi-axles. Fig. 75 10 is a cross section of the junction (Fig. 9). Fig. 11 a longitudinal section thereof.

Referring to Figs. 1, 2 and 3 the rigid framework surrounding the wheels 12 consists of four bars or stays 13 and integral with the two girders 14 parallel to the line of semi-axles 15. The bars or stays 13 contain the bearings 16 and upon which are affixed the springs 17 supporting the carriage body 18 and have grooves 19 for the horn plates 20 to slide in. Thus it will be seen that the bearings together with the bars or stays and the girders form a rigid framework surrounding the wheels. The helical springs 21 are attached at the junctions of 90 the bars or stays 13 and girders 14 and held in vertical position by their top ends fitting in sockets 22 on the carriage body 18, (see Fig. 3) and may be used with or without the springs 17. The rigid framework also 95 carries the hangers 23 supporting the brake bar 24 of the brake blocks 25 (see Fig. 3).

Referring to Figs. 4, 5 and 6 the bogie has surrounding each pair of wheels a rigid framework as hereinbefore described. These 100 frames are connected together by bars stays or bolts preferably as shown in Figs. 4, 5 and 6 wherein the connection consists of two plate bars 26 and 27 the top bar having U-shaped bends 28 taking around three sides 105 of the girder 14 and having sufficient space 29 between the vertical limbs of the U-shaped bends 28 and the girder 14 to allow of any radial action present. This top plate 26 is bolted to the bottom plate by bolts 30. 110

Referring to Figs. 7 and 8 the bearings 16 being U-shaped have top and bottom brasses 31 and 32 respectively surrounding entirely the semi-axles 15 and are held together by a bridge piece 33 fastened by bolts 34 to the bearing 16. The inner surfaces of the brasses 31 and 32 have a groove 35 which is widened in the bottom brass 32 to form an oil well 36. Within this groove 35 and oil well 36 revolves a collar 37 of a smaller dimension and loosely attached to the semi-axle 15 thereby constantly lifting the oil. From the bottom of the oil well 36 leads a tube 38 containing cotton or other capillary fabric to an oil cup 39 secured to the top of bearing block 16. The bearing 16 and top brass 31 have oil passages 40. The end or outside bearings (see Fig. 8) has a box 41 attached to the bearing 16 and contains a U-shaped keeper 42 fitting over the 130

groove 43 of the semi-axle 15 to prevent excessive lateral thrusts of the said semi-axles. Thus it will be seen that these bearings will firmly secure the semi-axles 15 to the rigid framework and at the same time allow rotation.

Referring to Figs. 9 to 11 wherein the semi-axles partly telescope one another the internal end of one semi-axle is somewhat enlarged and is bored out forming an annulus 44 having a brass bush 45 to receive the reduced male member 46 of the corresponding semi-axle which abuts against the inner end of the female member and sufficient space between the faces of the annulus and corresponding semi-axle for lubricating the male member 46 within the brass bush 45. This junction is surrounded by a rectangular box consisting of two halves 47 and 48 bolted together by means of flanges 49 between which is packing 50. This box is held in position by bars or stays 51 bolted to the bars or stays 13. The flanges 49 of the ends of the box are shaped to the contour of the semiaxes and have grooves 52 for packing 50 thus making a dust proof box. The bottom half 48 of the box forms an oil well from which leads a tube 53 containing cotton or other capillary fabric and so conveys the surplus oil into the oil cup 54 attached to the top. Thus it will be seen that the axial line of the semi-axles is maintained.

Having now particularly described and ascertained the nature of my said invention and the manner in which it is to be performed I declare that what I claim is;

1. A railway car truck comprising two transverse bars and four cross bars, a bearing carried by each of said cross bars, brasses rigidly held in said bearings, a divided axle passing through said brasses, and wheels carried by said axle, said transverse bars,

cross bars, and bearing being integrally connected to each other.

2. A railway car truck comprising two transverse bars and four cross bars rigidly connected together, a bearing rigidly carried by each of said cross bars, brasses rigidly held in each of said bearings, a divided axle passing through said brasses, and wheels carried by said axle, the outer and inner cross bars being placed equidistant from their common wheel, and as close to the wheel as the construction of the car will permit.

3. In a railway car, a pair of trucks each comprising a rigid frame, a plurality of pairs of bearings rigidly carried on each of said frames, brasses carried by said bearings, a divided axle for each truck passing through the brasses carried thereby, wheels on said divided axles, and bars engaging with the adjacent part of the frame of each truck and allowing each frame to respond to the radial action of the wheels at curves.

4. A railway car truck comprising two transverse bars, four cross bars having their ends connected to the transverse bars, a bearing carried by each of said cross bars, an upper and lower brass in each bearing, a bridge piece holding the brasses in position, said transverse and cross bars, bearings, brasses and bridge piece being rigidly connected together, a divided axle passing through said brasses, and wheels carried by said axle, each semi-axle of the car abutting against its corresponding semi-axle.

In testimony whereof I have signed my name to this specification in the presence of two subscribing witnesses.

ARTHUR REGINALD ANGUS.
